UNITED STATES PATENT OFFICE.

WILLIAM OTTO FRAGMEIER AND OTTO GUSTAVE MUHLIG, OF PORTLAND, OREGON.

SPIKE-MAKING DEVICE.

1,273,760.

Specification of Letters Patent. Patented July 23, 1918.

Application filed January 8, 1918. Serial No. 210,876.

To all whom it may concern:

Be it known that we, WILLIAM OTTO FRAGMEIER and OTTO GUSTAVE MUHLIG, citizens of the United States, and residents of Portland, in the county of Multnomah and State of Oregon, have invented certain new and useful Improvements in Spike-Making Devices, of which the following in a specification.

10 Our invention is an improvement in spike making devices, and has for its object to provide a device of the character specified, by means of which two spikes may have their points simultaneously cut and pointed, 15 without leaving any flare, fin or other superfluous material, and wherein two spikes may be formed at once.

In the drawings:

Figure 1 is a top plan view of the device, 20 with the parts of the mold separated;

Fig. 2 is a longitudinal vertical section, with the mold sections closed;

Fig. 3 is a perspective view of the mold with a portion of one section cut away; and

25 Fig. 4 is a perspective view of the point of a spike.

In the present embodiment of the invention, the mold is sectional, consisting of similar sections 1 and 2, each of which is rabbeted at one edge, as indicated at 3, and the sections are so arranged that the rabbeted portions thereof will fit each other in the manner shown in Fig. 2. Each section is recessed, as indicated at 4, at the angle of 35 the rabbet, to receive the tools or dies 5 which are similar and of self-hardening tool steel. These dies 5 are held in place in the recesses 4 by means of screws 6 which are passed downwardly through registering 40 openings in the dies and in the sections of the mold, in such manner that the dies may be easily removed when desired.

Each die, as shown more particularly in Figs. 1 and 2, has at its center and on its 45 outer edge a substantially triangular extension 7, and the said extensions form at their apices cutting edges to separate a bar 8 of metal from which two spikes are to be formed. This bar is placed in the mold between the die sections, being heated to a suitable temperature, and the sections are then forced together in any suitable manner, until the points of the extensions 7 meet to cut the bar 8 in two, thus forming two spikes.

50 Since the sections of the mold which, in practice, are cast iron or the like, lap over

and cover the open top and bottom of the space between the die sections, and the die sections themselves form an unyielding wall at the opposite sides of the spike, the bar 8 60 will be cut into two perfectly formed spikes, without any flare at the point 9 of the spike, and without any fin or superfluous metal. The ends of the bar may be headed at each end of the die, as shown at 10 in Fig. 1, and 65 the bar may be headed before or after it is cut. The sections of the mold are moved toward and from each other in any suitable or desired manner, as, for instance, by means of links 11, which have the ends adjacent 70 to the sections received between spaced lugs 12, and a bolt 13 is passed through registering openings in the lugs and in the link and engaged by a nut 14 to hold the parts together. 75

The outer end of each link is connected to an eccentric secured to a shaft 15, and these shafts may be driven in any suitable or desired manner.

The improved device is especially adapted 80 for small plants, having no special machines, where the heads of the spikes are made in various ways, and the point in a separate operation, generally by the use of a small trip hammer. With the present construction, 85 two spikes may be made at one operation, and with perfectly formed points.

We claim:

1. A device of the character specified, 90 comprising similar mold sections, said sections being rabbeted on their meeting edges to lap one upon the other, and each being recessed at the angle of the rabbet to receive a die, dies detachably held in the recesses at the rabbeted face, each die having at the 95 center of the edge adjacent to the other die a triangular extension adapted to abut at its apex the apex of the extension of the other die to cut a bar to form two spikes, the space between the dies extending to the ends of the 100 mold sections to permit the bar to extend beyond said sections to permit the formation of a head at each end of the bar.

2. A device of the character specified, 105 comprising similar mold sections, said sections being rabbeted on their meeting edges to lap one upon the other, and each being recessed at the angle of the rabbet to receive a die, dies detachably held in the recesses at the rabbeted face, each die having at the center 110 of the edge adjacent to the other die a triangular extension adapted to abut at its

apex the apex of the extension of the other die to cut a bar to form two spikes, and means for moving the sections toward each other and for guiding them in their movement.

3. A device of the character specified, comprising similar mold sections, said sections being rabbeted on their meeting edges to lap one upon the other, and each being

recessed at the angle of the rabbet to receive 10 a die, dies detachably held in the recesses at the rabbeted face, each die having at the center of the edge adjacent to the other die a triangular extension adapted to abut at its apex the apex of the extension of the 15 other die to cut a bar to form two spikes.

WILLIAM OTTO FRAGMEIER.
OTTO GUSTAVE MUHLIG.
